UNITED STATES PATENT OFFICE.

CHARLES B. WANAMAKER, OF INDIANAPOLIS, INDIANA, ASSIGNOR TO LEEDY MANUFACTURING COMPANY, OF INDIANAPOLIS, INDIANA, A CORPORATION OF INDIANA.

SNARE-DRUM.

1,144,452.

Specification of Letters Patent Patented June 29, 1915.

Application filed December 19, 1913. Serial No. 807,584.

To all whom it may concern:

Be it known that I, CHARLES B. WANAMAKER, a citizen of the United States, residing at Indianapolis, in the county of 5 Marion and State of Indiana, have invented a new and useful Snare-Drum, of which the following is a specification.

The object of my invention is to produce a drum having an improved form of tension 10 means by which variations in the condition of the drum heads will be automatically compensated, and to provide means by which the tension of the snares will be automatically maintained.

15 A further object of my invention is to produce as an improved article of manufacture a neat and compact tension member for drums.

The accompanying drawings illustrate 20 my invention.

Figure 1 is a head elevation of a tenor drum constructed in accordance with my invention; Fig. 2 a side elevation; Fig. 3 a section, about full size, of my improved tension device and associated parts; and Fig. 4 a partial section showing the relative arrangement of the snares and head rings where they pass each other.

In the drawings, 10 indicates the main 30 body of a drum and 11, 11 indicates the heads thereof, the edges of said heads being engaged, in the usual manner, by the head rings 12, 12 which embrace the main body 10. These rings may be of sufficient width 35 to receive my improved tension devices but I prefer to provide an additional ring 13 to coöperate with each ring 12, the ring 13 being formed of light angle iron having a horizontal inwardly projecting flange 40 adapted to overlie the adjacent head ring 12. Thus far the construction is substantially that shown in my Patent No. 1,031,032.

My improved tension device comprises a spring 21 which may be placed under tension by opposing members which engage, 45 and tend to draw together, the two rings 13 with the yielding pressure of the spring 21 so that, as the skins 11 tend to loosen or tighten under varying weather conditions, 50 the springs 21 will permit a yield of the rings 13 axially of the main body of the drum to compensate for the change in condition of the skins.

In order to make a sightly construction and one which can be readily applied to existing drums and which can be easily handled without having its parts become separated, I prefer to employ a plurality of particular spring constructions shown in detail in Fig. 3, the various parts of which can 55 be readily produced at minimum cost and easily assembled. In this preferred form of tension device I provide two similar heads 25, 25 each of which is axially threaded and provided on its outer end with an annular axially-projecting flange or rib 26. Threaded into the heads 25, 25 are the screws 27 and 28 which pass through suitable openings in the horizontal flanges of the rings 13, the screw 28 being conveniently provided with a knurled head 29 by means of which it may be readily turned so as to adjust the tension of the spring 21. The barrel of the tension device is composed of four sheet metal segments 30 which are 70 pressed into cylindrical segments and have their ends turned inwardly to form segmental hooks which may either take over the ribs 26 of heads 25 or over the coils of the spring 21. Two diametrically opposite 75 segments 30 are then hooked over the rib 26 of one head and over the opposite end of spring 21, while the other two segments 30 are hooked over the rib 26 of the other head and over the opposite end of spring 21, this 80 last operation being accomplished by first compressing the spring slightly so that when the parts are released each head 25 85 will be held against the adjacent end of the spring and the spring will be under slight 90 compression, thus holding the parts firmly in place so that the article may be readily handled and shifted without becoming dismembered.

In order that the snares 40 may have a 95 uniform effect on the drum head they are mounted in brackets secured to the body of the drum instead of to the head rings and in Fig. 2 I show one of these brackets 41 as a support for a screw 42 which passes 100 freely through the bracket and is threaded into the cross bar 40' of the snares. Between the head of screw 42 and the bracket 41 I arrange a spring 43 the tension of which may be adjusted by an adjustment of 105 screw 42 and this spring serves to keep the

snares at desired tension irrespective of the movement of the head rings permitted by my improved tension device.

I claim as my invention:

- 5 1. As an article of manufacture, a tensioning member for drums comprising a pair of threaded heads, an interposed spring, and a multiplicity of mating barrel-forming members each comprising a sheet metal portion formed into a cylindrical segment and having inwardly turned hooks at its opposite ends, one hook of each of said members engaging a head and the other hook of each of said members engaging the spring.
- 10 2. As an article of manufacture, a tensioning member for drums comprising a pair of threaded heads, an interposed spring, and a multiplicity of mating barrel-forming members, each having inwardly turned hooks at its opposite ends, one hook of each of said members engaging a head and the other hook of each of said members engaging the spring.
- 15 3. As an article of manufacture, a tensioning member for drums comprising a pair of heads, a compression spring between said heads, a plurality of members extending along the outside of said spring and each having hooks at both ends, some of said members being hooked to one of said heads and to the opposite end of said spring and the remainder of said members being interspersed with them and hooked to the other head and the end of the spring opposite therefrom, said spring being sufficiently long when expanded to force the ends of said members which engage it against said heads.
- 20 4. As an article of manufacture, a tensioning member for drums comprising a pair of heads, a compression spring between said heads, a plurality of members extend-

ing along the outside of said spring and each having hooks at both ends, some of said members being hooked to one of said heads and to the opposite end of said spring and the remainder of said members being interspersed with them and hooked to the other head and the end of the spring opposite therefrom.

45

5. A drum comprising a main body, a pair of heads, a head ring for each of said heads, means for resiliently urging these head rings toward head-tightening positions, snares coöperating with one of said heads, and resilient means for tightening said snares independently of either head ring.

50

6. A drum comprising a main body, a pair of heads, a head ring for each of said heads, means for resiliently urging these head rings toward head-tightening positions, snares coöperating with one of said heads, and means for tightening said snares independently of either head ring.

55

7. A drum comprising a main body, a head, a head ring coöperating with said main body and head, means for adjusting the head ring upon the main body to vary the tension of the head, snares associated with said head, resilient means for tightening said snares, and a support for said snare whereby adjustment of the drum head will not vary the tension of the snares.

60

In witness whereof, I have hereunto set my hand at Indianapolis, Indiana, this 17th day of December, A. D. one thousand nine hundred and thirteen.

65
